WOOD WASTE DISPOSAL APPARATUS

Guy A. Boughman, Lenoir, N. C., assignor, by direct and mesne assignments, to Boughman Machine Company, Lenoir, N. C., a corporation of North Carolina

Application November 14, 1946, Serial No. 709,811

4 Claims. (Cl. 302—50)

1

This invention relates to means for handling shavings and other waste products from wood-working machines, such as sawdust, chips, or any wooden particles derived from the finishing of wood or the manufacture of wood into furniture wherein there are chips, shavings, sawdust and other wood refuse.

Heretofore in woodworking establishments, such as furniture factories, the disposition of the wood waste from the woodworking machines has been quite a problem. It has heretofore been taken usually by suction from the woodworking machine and conveyed to a suitable place outside the building where it has been dumped into a large pile, which creates quite a fire hazard and, in fact, such disposition of the waste of the woodworking plant is not favored by insurance companies. Other means of disposing of this waste has been in conveying the shavings by suitable means to a furnace and endeavoring to burn the shavings and wood waste in a furnace. Usually these shavings have been thrown into the furnace by shovel, or otherwise, and are in great packed masses or lumps and would not properly burn, thus creating quite a problem in the disposition of the shavings.

It is an object of the present invention to provide a storage compartment, or bin, into which shavings may be conducted for storage and providing a screw conveyor in the lower end of the storage bin for withdrawing the shavings from the storage bin and providing a plurality of stirring elements disposed above the conveyor to stir the shavings and to prevent their being conveyed in large lumps. From the conveyor the wood waste is received by suction and blowing means which conveys the wood waste from the end of the conveyor disposed on the exterior of the storage bin to the fire box of a furnace where these disintegrated shavings or wood waste are delivered into the furnace in a scattered and finely divided condition, and at a rate at which the shavings can be consumed and thus providing not only trouble-free means of disposing of the shavings but also providing a source of heat for heating the building and for generating steam for driving of electrical generators and the like, thus eliminating the necessity of hiring labor for disposing of the shavings, but in addition deriving from these shavings sufficient power not only to heat the building from whence the waste came but also to generate a large portion of the electrical current used in the building.

It is another object of this invention to provide means for removing shavings and other wood

waste from a storage bin and conveying them to a furnace in a finely divided condition where they will be burned for the generation of heat.

It is another object of the invention to provide means for feeding wood waste to a furnace comprising a conduit for receiving the waste and having a suction blower fan therein whose intake end is connected to the other end of the conduit, said conduit having a vane pivoted at one end in the conduit and having its free end adapted to rest on the waste passing through the conduit, the suction blower fan having a discharge conduit leading to the furnace. The use of the vane confines the air currents against the waste on the bottom of the conduit and thus eliminates the need for a "Cyclone" or centrifugal separating apparatus in the discharge conduit.

Some of the objects of the invention having been stated, other objects will appear as the description proceeds when taken in connection with the accompanying drawings, in which

Figure 1 is a side elevation of the invention with portions broken away;

Figure 2 is a top plan view of the left-hand portion of Figure 1 and omitting the storage bin walls;

Figure 3 is an elevation looking from the left-hand end of Figure 2, and omitting the storage bin;

Figure 4 is an enlarged elevation of the right-hand portion of Figure 1;

Figure 5 is a vertical sectional view taken along the line 5—5 in Figure 4;

Figure 6 is an elevation, partly in section, and taken along the line 6—6 in Figure 3;

Figure 7 is a top plan view of the structure shown in Figure 4 and showing the walls of the storage bin in section;

Figure 8 is a longitudinal sectional view through the funnel and a portion of the conveying means, taken along the line 8—8 in Figure 2, but omitting portions of the upper portion of the structure shown in Figure 2;

Figure 9 is a vertical sectional view taken along the line 9—9 in Figure 1;

Referring more specifically to the drawings, the numeral 10 indicates a suitable storage bin of any desired height into which the shavings, chips, sawdust, and other wood waste may be projected, such as through a pipe 11. One of the walls of the storage bin 10 has a suitable opening 12 therein, through which a conveyor mechanism is adapted to pass and it also has a suitable hole 13 through which a stirrer shaft may be passed.

The conveyor mechanism comprises a semi-circular trough 15 having angle irons 16 and 17 disposed on each side thereof to which the semi-circular trough 15 is secured as by spot-welding. Spot-welded to these angle irons 16 and 17 is a plurality of semi-circular support members 18 which have welded between their lower portions suitable angle members 20 to provide a framework for the trough 15. Suitable legs 21 are welded to the angle bars 16 and 17 and rest on the floor of the bin for supporting the trough.

Rotatably mounted in the trough 15 is a screw conveyor 23 which has its right-hand end mounted in a suitable bearing block 24 which is secured on a plate 25 secured between the outer ends of angles 16 and 17 and closing the right-hand end of the trough in Figures 1 and 4. The other end of the screw conveyor 23 is mounted in a bearing block 27 secured on a plate 28, which plate is welded to the proximate edges of angles 16 and 17 in Figures 1 and 2. The clearance between the screw conveyor and the inside surface of the trough prevents the wood waste from packing together and adhering to the screw conveyor. The trough itself stops short of the left-hand ends of the angle irons 16 and 17 so that the shavings may dump from the open end thereof into a suitable funnel to be presently described so excess shavings can spill over the sides of the funnel and prevent clogging. The screw conveyor 23 has secured thereon a sprocket wheel 30, having a sprocket chain 31 thereon which is mounted on a sprocket wheel 32 on a stirrer shaft 33. Near the outer end of the shaft 33 a bearing block 35 is disposed which is secured to the upper end of the plate 28.

Secured to and arising from angle bars 16 and 17 are bars 36 and 37 which support angles 42 and 43 which support a plate 38. Disposed between the angles 42 and 43 and angles 16 and 17 respectively, are plate members 48 and 49 which define a passageway of sufficient clearance to prevent parking of shavings through which the shavings or other wood wastes pass through the opening 12 in bin 10. Suitable brace bars 40 and 41 are secured to the upper surfaces of plate 38 and to the plate 28.

The rear end of the stirrer shaft 33 is supported in a bearing 47 mounted in the upper end of plate 25, which plate is braced by suitable supports 50 and 51 secured to plate 25, and to the top surfaces of angle bars 16 and 17. The stirrer shaft 33 has a plurality of toothed disks 53 mounted thereon for stirring the shavings in the lower portion of the bin, immediately above the screw conveyor 23 to cause the shavings to be broken up before they are withdrawn from the bin by the screw conveyor 23.

The outer end of the screw conveyor shaft 23 has mounted thereon a beveled gear 60 which meshes with the beveled gear 61 projecting from a reduction gear housing 62 which has a V-pulley 63 thereon, on which V-belts 64 are mounted and which V-belts are also mounted on a suitable V-pulley 67 mounted on a motor shaft 68 of an electric motor 70 supported on a suitable angle framework 71. This imparts rotation to screw conveyor and also to stirrer shaft 33.

Disposed below the open end of the trough 15 and on the outside of the bin 10 is a funnel 75 which empties into a rectangular tube 76 which has a vane 77 pivoted as at 78 therein, and the tube 76 has an opening 80 therein, closed by a suitable cap closure 81 which may be opened if desired to clean the interior of the tube 76. The

funnel forms an air inlet opening which pulls shavings into the tube 76.

The vane 77 also acts as a check valve against explosions or blow backs from the furnace. Rising upwardly from the left-hand portion of tube 76 in Figure 8 is a pipe 83 which extends into a suction blower casing 84 which has rising therefrom a discharge pipe 85 which leads to a suitable furnace 87 having a fire box 89 with grates 88 therein. The discharge end of the blower pipe 85 is substantially larger in diameter than the conveyor pipe 85, preferably about twice the diameter of the conveyor pipe 85 so as to cause the wood waste and the air blasts to decrease in velocity immediately prior to entering the fire box 89 of the furnace and also to create turbulence. This allows the shavings and other wood waste to slide or roll onto the burning shavings already within the fire box and without disrupting the shavings to any great extent.

Disposed within the suction blower fan housing 84 is a conventional blower, not shown, which is mounted on a shaft 93. The shaft 93 has disposed thereon on the exterior of the housing 84 a pulley 94 having a belt 95 thereon which is also mounted on a pulley 96 disposed on motor shaft 97 of an electric motor 98.

It is to be noted that the vane 77 pivoted as at 78 in the conduit 76 normally occupies the position shown in bold lines in Figure 8 due to gravity when there is not an excess of air velocity in the end of the conduit which is disposed next to the intake side of the suction blower fan. However, when there is a reduction in the air velocity in the left-hand end of the conduit of Figure 8, then the vane 77 will tend to fall by gravity to the position shown in the drawings. During normal operation, the free end of the vane 77 will tend to rest on the layer of waste traveling along the bottom of the tube 76, but the suction will keep digging the waste from beneath the free end of the vane 77 as the vane localizes the air currents at the free end of the vane.

It is thus seen that I have provided a novel apparatus for the handling of wood waste in working plants whereby the wastes can be stored in a suitable bin and disintegrated and stirred up and removed from the bin and conveyed to the fire box of a furnace in an economical and feasible manner so that the wood waste will be properly consumed by the fire in the fire box and will not smoke and smolder in the fire box as heretofore has been the case. Also, what was heretofore considered a liability in the matter of disposal has been converted into an asset in that the wood waste is handled and disposed of at very low cost, and the waste is converted into heat energy, thus replacing valuable heat energy in the form of coal for the heating of buildings and in the form of electric current which heretofore has been bought from the power company.

In the drawings and specification I have shown a preferred embodiment of the invention, and although specific terms are employed, they are used in a generic and descriptive sense only, and not for purposes of limitation, the scope of the invention being defined in the claims.

I claim:

1. Apparatus for conveying wood waste comprising a conduit having an open intake end and having the suction side of a suction blower fan connected to its other end, said fan having one end of a discharge conduit connected to the output side of the fan, the other end of the discharge conduit having a diameter greater than that of

the other portions of the discharge conduit, said conduit having a vane pivoted therein at one of its ends on a transverse horizontal pivot and so mounted that its free end is allowed to rest by gravity on the wood waste on the bottom of the conduit for regulating the amount of vacuum in the conduit.

2. Apparatus for conveying wood waste comprising a conduit having an open intake end directed upwardly and into which wood waste may fall by gravity, a suction blower fan having an inlet port and an outlet port, the other end of the conduit being connected to the inlet port of the fan, a discharge pipe having an end connected to the outlet port of the fan, the other end of the discharge pipe being of greater diameter than the main portion of the discharge pipe, the conduit having a vane of greater overall height than the height of the conduit and pivoted on a transverse pivot at its upper end near the top of the conduit and having its free end extending towards the fan and adapted to rest on the waste passing along the conduit to confine the induced air currents against the wood waste and whose free end will rise as a result of the induced air currents in the conduit.

3. Apparatus for conveying wood waste from a woodworking plant, such as shavings, chips, and the like, comprising a suction blower fan having an intake conduit, the intake end of which is provided with a funnel into which the wood waste is adapted to be dumped, the suction blower fan having a discharge conduit leading therefrom, the end of the discharge conduit being of larger dimensions than the rest of the discharge conduit to create turbulence and to lessen the air velocity passing out of the end of the discharge

conduit, the intake conduit between its intake end and its connection to the suction blower fan having a vane therein pivoted near its upper end on a transverse pivot near the top of the conduit and said vane being of substantially the same width as the inside dimensions of the intake conduit, said vane extending towards the fan and its lower end being adapted to rest by gravity on the wood waste being drawn through the intake conduit to thereby confine the air currents against the top of the wood waste being conducted along the bottom of the intake conduit.

4. Apparatus for conveying wood waste, such as shavings, sawdust, chips and small pieces of wood comprising an intake conduit having one end open for receiving the waste, a suction-blower fan having its intake end connected to the other end of the intake conduit, said fan having one end of a discharge conduit connected to its discharge end and said conduit having its other end enlarged, a vane pivoted at one of its ends on a transverse pivot in close proximity to the top interior wall of the intake conduit and having its free end extending towards the fan and adapted to rest by gravity on the waste moving along the bottom of the intake conduit.
